CLAIM

The ornamental design for a fitting for a furnishing, as shown and described.

DESCRIPTION

FIG. 1 is a plan view of a fitting of a furnishing of the present invention;

FIG. 2 is a front view of the fitting of a furnishing of FIG. 1;

FIG. 3 is a side view of the fitting of a furnishing of FIG. 1;

FIG. 4 is a side view in a direction opposite to that of FIG. 3 showing the fitting of a furnishing of FIG. 1;

FIG. 5 is a first perspective view of the fitting of a furnishing of FIG. 1; and,

FIG. 6 is a second perspective view of the fitting of a furnishing of the invention of FIG. 1.

1 Claim, 6 Drawing Sheets
